PANEL

Carroll V. Sweet, Madison, Wis.; dedicated to the free use of the People in the territory of the United States

Application July 16, 1941, Serial No. 402,706

3 Claims. (Cl. 20—4)

(Granted under the act of March 3, 1883, as amended April 30, 1928; 370 O. G. 757)

This application is made under the act of March 3, 1883, as amended by the act of April 30, 1928, and the invention herein described and claimed, if patented, may be manufactured and used by or for the Government of the United States of America for governmental purposes without the payment to me of any royalty thereon.

I hereby dedicate the invention herein described to the free use of the People in the territory of the United States to take effect on the granting of a patent to me.

This invention relates to panel construction, and more particularly to the construction of the individual panels.

One of the objects of this invention is the provision of a panel which can be fabricated of small inexpensive pieces of wood.

Another object of this invention is the provision of a panel prefabricated with an insulating backing.

In the accompanying drawing there is illustrated an embodiment of this invention, in which:

Figure 1 is an isometric view of a panel constructed in accordance with this invention with the back thereof facing upward.

Figure 2 is a rear elevational view, partly in section.

Figure 3 is a section along the line 3—3 of 30 Figure 2.

Figure 4 is a section along the line 4—4 of Figure 2.

Referring with more particularity to the drawing in which like numerals designate like parts, the embodiment illustrated comprises a panel fabricated of a plurality of crosspieces 11 connected by means of tongue and groove joints 12. On the back of the connected crosspieces 11 a sheet 13 of fabric or building paper, or other suitable material, is disposed, which is held in place together with the crosspieces 11 by means of two longitudinal cleats 14, 14. Each crosspiece is secured to the cleats by nails 15 disposed first through apertures 16 in the cleats with the point of the nails embedded in the crosspieces after passing through the sheet 13. To prevent strain under atmospheric changes, the apertures 16 are made slightly larger than the nails 15 or are slotted in a longitudinal direction with respect to the panel.

The heads of the nails 15 are preferably countersunk in the cleats 14 so as not to protrude beyond said cleats. If a wider bearing surface is desired, washers (not shown) may be disposed between the heads of the nails and the cleats. If desired, screws may be used instead of the nails 15.

Between corresponding ends of the cleats 14, 14 cross cleats 17, 17 are secured to the panel forming a box construction within which insulation material 18 of the fill type, such as sawdust, wood shavings, mineral wool, peat moss, or other vegetable or mineral fiber, is compressed and covered with a sheet 19 of fabric or building paper. The sheet 19 extends over the sides of the cleats 14, 14 and 17, 17 and is secured thereto by means of laths or strips 20 nailed through said strips and through sheet 19 into the said cleats, substantially as illustrated. If desired, sheet 19 may be glued to the cleats or secured thereto in any other suitable manner.

15 Panels constructed in this manner may be used for either interior or exterior construction. When used for interior construction, the sheet 13 should be of a highly moisture resistant type to prevent moisture from the interior of the building condensing on the insulation or in the outer wall behind it as it is cooled to the dew-point by outdoor temperatures. The sheet 19 should be of a non-moisture resisting or porous type to permit "breathing" of the insulation into the hollow wall space. For use in exterior construction, such as for exterior walls and roofing, the types of materials used for the sheets 13 and 19 should be the reverse of that described for interior use.

Having thus described my invention, I claim:

1. A building panel comprising a plurality of crosspieces, longitudinal cleats secured to the back of said crosspieces, cross cleats secured at the ends of said longitudinal cleats, all of said cleats forming a box, a sheet of material between said cleats and said cross pieces, insulating material in said box, and a cover sheet over said cleats and insulating material.

2. A building panel for interior construction comprising a plurality of crosspieces, longitudinal cleats secured to the back of said crosspieces, cross cleats secured at the ends of said longitudinal cleats, all of said cleats forming a box, a sheet of moisture resistant material between said cleats and said crosspieces, insulating material in said box, and a porous cover sheet over said cleats and insulating material.

3. A building panel for exterior construction comprising a plurality of crosspieces, longitudinal cleats secured to the back of said crosspieces, cross cleats secured at the ends of said longitudinal cleats, all of said cleats forming a box, a sheet of porous material between said cleats and said crosspieces, insulating material in said box, and a moisture resistant cover sheet over said cleats and insulating material.

CARROLL V. SWEET.
